SEALING STRIP SEVERING MACHINE

David Brody, Clinton, Mass., assignor to Van Brode Milling Co., Inc., Clinton, Mass., a corporation of Massachusetts

Application October 24, 1950, Serial No. 191,821

2 Claims. (Cl. 164—84.5)

1

The present invention relates to improvements in machines for sealing boxes having hinged covers.

One of the objects of the invention is to provide a machine of novel, simple and inexpensive construction for applying a sealing strip or tape to boxes of the type mentioned in a manner to secure the covers thereof in closed position so as to prevent opening of the boxes without mutilating the closure.

Another object of the invention is the provision of a machine of the character indicated which is entirely automatic in its operation.

A further object of the invention is to provide a novel sealing machine, wherein the sealing strip or tape is unwound from a supply reel by the boxes themselves and which is, after being applied to a box, severed from the remainder without the use of cutting tools.

Generally speaking, the invention consists in the combination of a mechanism for folding the box cover to closing position, with means for holding the cover in its closing position while a sealing strip is being applied to the box, and a device for severing the strip of a sealed box from those of the boxes following by causing the last sealed box in the series to drop a distance sufficient to tear its sealing strip from that applied to next box following in the cycle of operation of the machine.

One of the many possible embodiments of the invention is illustrated in the accompanying drawings, in which:

Figure 1 is a perspective view of the box closing and sealing strip applying mechanisms of the machine;

Figs. 2 and 2a show a side elevation of the complete machine, divided along line A—A shown both in Figs. 2 and 2a;

Fig. 3 is a side elevation of the element for shifting the box covers toward closing position;

Fig. 4 is a side elevation of a roller for completing the closing movement of the box cover and for causing the cover flap to rest on the box body;

Fig. 5 is a front elevation of the roller shown in Fig. 4;

Fig. 6 is a section taken on line 6—6 of Fig. 2;

Fig. 7 is a perspective view of a row of boxes as they pass through the machine, showing the elements thereof in successive stages of operation;

Fig. 8 is a section taken on line 8—8 of Fig. 2, on a larger scale;

Fig. 9 is a section taken on line 9—9 of Fig. 2;

2

Fig. 10 is a top elevation of the strip severing portion of the machine; and

Fig. 11 is a section taken on line 11—11 of Fig. 10.

The novel machine, forming the subject matter of the present application for Letters Patent, is particularly efficient in sealing boxes 20 of the type shown in detail in Fig. 7 of the drawings, which includes a closing cover 21, hinged along one of its edges, denoted by the numeral 22, to one of the sides of the box body, and having at its opposite edge 23 a flap 24, which bears against the side 25 of the box body, when the cover is in its closed position. The box side 25 is opposite to that side of the box body to which the cover is hinged.

The improved machine includes two supporting frames 26 and 27, each mounted on legs 28. The frames are longitudinally aligned, the frame 26 being disposed in front of the frame 27. Each frame is provided with an endless conveyor 29, the width of which corresponds substantially to the width of the boxes to be sealed. The conveyors are disposed end to end in close proximity to one another, so that the boxes are adapted to travel from that of the frame 26 to the one mounted on the frame 27. Each conveyor passes over rollers 30 and is operated in any convenient manner, for instance by operatively connecting the shaft 31, to which one roller is fixed, with a suitable source of power, such as an electric motor, not shown.

Referring now to the conveyor 29 associated with supporting frame 26, guide rails 32 extend lengthwise of said frame in operative relation to and along the opposite longitudinal edges of the upper run of said conveyor. The guide rails are spaced apart a distance exceeding the width of the boxes to be sealed. The upper run of said conveyor moves in the direction of the arrow shown in Fig. 1 of the drawings, thereby transporting the boxes placed thereon at the front end 33 of the frame 26 toward and onto the conveyor associated with the supporting frame 27. The boxes are placed, one after another, upon the conveyor with the cover flaps 24 thereof extending longitudinally of the conveyor, the covers being partly closed, as shown in Fig. 1 and at the right-hand end of Fig. 7. Immediately in rear of the entrance end of the machine is located an inclined deflector 34, which extends between and longitudinally of the guide rails 32, its front end 35 being fixed to a bracket 36, mounted upon one of the rails 32, and its rear end 37 resting upon

55 a bar 38. The bar 38 runs across the supporting

frame 26 and is carried by brackets 39 on the rails 32 at a height to contact the box covers before they are forced, by means presently to be described, to their fully closed position. The front portion of the deflector 35 is located a substantial distance above the upper run of the conveyor, more particularly at a distance to enable the operator conveniently to engage the leading edge of the inclined box cover with the deflector as the box is being placed by hand on the conveyor.

In rear of the deflector 34 is disposed a roller 40, the shaft of which is journaled in one of the brackets 39. This roller is provided with a reduced section 41, the cylindrical face of which is adapted to act upon the exposed face of the box cover, to force the cover against the top of the box body, and a flat face 42, acting upon the exposed face of the cover flap 24 to cause the same to lie against the box side 25 (see Fig. 8).

Behind the roller 40 are mounted upon the guide rails 32 two longitudinally disposed metal frames 43, which, in conjunction with said rails, carry two sets of vertically arranged rollers 44, one set on each guide rail 32. These two sets of rollers are spaced apart a distance properly and without undue friction to guide the boxes in their travel through the machine. On each frame 43 is mounted a spring-pressed angle iron 45, carrying horizontally arranged rollers 46, which extend across the supporting frame 26 in contact with the covers of the boxes traveling under the same and thereby maintaining the covers in their fully closed position, while one set of the vertical rollers 44 holds the cover flaps 24 against the box sides 25.

As the boxes pass through the guideway defined by the rollers 44 and 46 and while the box covers are held by these rollers in their closing position with the flaps 24 against the box sides 25, a sealing strip 47 is applied to the same. This strip is, preferably, made of paper of a suitable thickness and is provided on one face thereof with a coating of adhesive material, which is being moistened while the strip is transferred from a reel to the box sealing machine, entering the latter through a slot 48 in one of the metal frames 43. The adhesive strip supplying and moistening means may be of any suitable construction and needs no further description as, per se, it does not constitute a novel feature of the instant machine. The sealing strip is applied to a box by being extended longitudinally upon its cover flap and the adjacent portion of the box side 25.

The set of rollers 44, mounted on that frame 43 which is provided with the slot 48 above referred to, serves initially to supply pressure to and hold in place the sealing strip, supplemental means being provided to apply additional pressure, whereby the adhesive application of the sealing strip to the boxes will be insured. The supplemental pressure applying means comprises a flat spring 49, carried by one of the guide rails 32, and a set of stiff-bristled brushes 50 on the guide rail on which the slotted frame 43 is disposed. The brushes serve also to remove any wrinkles and like defects in the applied sealing strip with the result that the latter is smoothly and uniformly applied to the boxes. While the boxes travel past the brushes, they are held down on the conveyor by a horizontal bar 51, extending longitudinally above the machine between the rails 32 and being secured to a bracket 52 on the latter.

The sealed boxes pass onto the conveyor carried by the supporting frame 27, being guided in their movement on the latter by rails 53. Intermediate their ends, the said rails are connected, above the upper run of the conveyor, by a transversely extending bar 54 which is triangular in transverse cross-section, the apex of the triangle being located a substantial distance above the said upper run. In front of the said bar are located stops 55, carried by a bracket 56 on the guide rails 53. The stops extend from the bracket downwards almost into contact with the box tops as said boxes travel along the machine, and the distance between the apex of the bar 54 and the lowermost edges of the stops 55 is less than the length of an individual sealed box.

The operation of the improved machine is as follows:

The filled boxes are placed by the operator, one after the other, on the upper run of the conveyor associated with the supporting frame 26 with their covers in partly closed position and with the leading edges 21' of said covers touching the underside of the deflector 34. As a box is being advanced by the conveyor in the direction of the arrow shown in Fig. 1 of the drawings, the said deflector shifts the box cover towards and nearly to closing position, the transverse bar 38 maintaining it in such position in readiness for the operation of the roller 40, which completes, in the manner hereinabove described, the closing operation preparatory to the application of the sealing strip.

Before the operation of the machine is started, the sealing strip must be passed through the slot 48 in the metal frame 43, to be picked up by the first box advancing through the guide formed by the rollers 44 and 46 and to be applied to the box by the set of rollers 44 associated with the last-mentioned metal frame. Once the strip is attached to a box, it is automatically presented by each box for application to the next box in the series.

The sealing strip having been applied to a box, the latter, in its continued travel through the machine, is subjected to the action of the set of brushes 50, which firmly fix the applied sealing strip in place on the box, at the same time removing any wrinkles and like defects which may have formed in the strip.

The boxes, connected by the sealing strip, pass then along onto the conveyor on the supporting frame 27. On this conveyor the boxes are automatically separated by the transverse bar 54 and the stops 55 co-operating with the latter. Each box, passing along the supporting frame 27, travels up the incline 57 of the bar 54 (see the box denoted by the character X in Fig. 11 of the drawings), and then drops back onto the conveyor, resting first with its leading edge on said conveyor, (see the box denoted by the reference character Y in Fig. 11 of the drawings). As the box drops into the last-mentioned position, the portion of the sealing strip between itself and the next box in the series is partly separated, the stops 55 preventing the upward movement of the rear end of the next box in the series. As the forward movement of the boxes continues, the last box in the series fully drops down onto the conveyor, whereby the tie between it and the next box in the series is broken, so that the box is ready for removal from the conveyor.

It is obvious that, while herein two separate conveyors have been disclosed, a single conveyor may be made use of without departing from the

invention. Also, details of construction of the various elements of the machine may be changed within the scope of the appended claims without departing from the spirit of the invention.

What I claim is:

1. In a sealing strip severing machine of the character described, the combination with a guide-way, of a belt conveyor for advancing a series of boxes connected by a continuous sealing strip along said guide-way, and a stationary transverse bar disposed above said conveyor and extending from side to side of the latter, said bar being triangular in cross section, said cross section including a base disposed parallel to and immediately above the box advancing portion of said belt conveyor, a side joining said base and rising therefrom to the apex of said triangular cross section, and a second side extending from said apex to the opposite end of said base, whereby each box is elevated by said transverse bar in its travel along said guide-way and then permitted by gravity to drop back onto said conveyor for breaking the connection between its sealing strip and that of the box following.

2. A machine for severing sealing strips according to claim 1, including stationary stops disposed in front of said bar and above the box

advancing portion of said belt conveyor, the distance between said stops and said conveyor being slightly greater than the height of an individual box and the distance between the apex of said bar and the said stops being less than the length of an individual box, whereby the rear end of a box the front of which rests on said bar is prevented from rising while the next preceding box in the series drops back from said bar onto said conveyor.
